CLAIM

The ornamental design for a fishing pole casting counter, as shown and described.

DESCRIPTION

FIG. 1 is a diagrammatic perspective view of the fishing pole casting counter in full lines with a fishing pole shown in broken lines representing environmental association matter being for illustrative purposes only and forming no part of the claimed invention;

FIG. 2 is a top plan view of the fishing pole casting counter;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.
